UNITED STATES PATENT OFFICE.

PAUL A. GOLLNICK, OF CHICAGO, ILLINOIS, ASSIGNOR TO SPIEGEL, MAY, STERN COMPANY, OF CHICAGO, ILLINOIS, A CORPORATION OF ILLINOIS.

TRAY.

Application filed June 11, 1927. Serial No. 198,171.

The main objects of this invention are to provide an improved form of tray for holding cards, stencils and the like which are filed vertically; to provide an improved construction and arrangement of a follower adapted to be shifted into engagement with one end of the stack of cards for holding them in compact form; to provide a follower of this kind having improved means for frictionally engaging certain portions of the tray; and to provide a tray having an improved form of guideway for the follower.

An illustrative embodiment of this invention is shown in the accompanying drawing, wherein:

Fig. 1 is a perspective of a tray and follower to which this invention is applied, part of one side of the tray being broken away, and the follower being shown in position for shifting.

Fig. 2 is a fragmentary view of the same, but showing the follower in its operative position.

Fig. 3 is an enlarged transverse section, taken on the line 3-3 of Fig. 2.

Fig. 4 is an enlarged top plan of a portion of the tray, showing the follower in its operative position, and showing a few cards supported in the tray.

Fig. 5 is an enlarged fragmentary perspective of the follower.

A tray embodying this invention is adapted for various uses, but in the specific construction herein shown it is particularly suitable for use in connection with addressing machine stencils.

In the embodiment herein illustrated, the invention is applied to a card and stencil holder comprising a tray 1, adapted for supporting a stack of cards 2, and having arranged therein a follower 3 which is movable into engagement with one end of the stack for holding the cards in compact form.

The tray 1 is preferably a sheet metal stamping formed to provide a bottom 4, end walls 5, and substantially parallel side walls 6. The upper edges of the side walls 6 are bent inwardly and downwardly to provide flanges 7 forming guides for the follower 3. Formed in the flanges 7 adjacent one end of the tray, are recesses 8 to permit removal of the follower from the tray.

The follower 3 is also preferably a sheet metal stamping having a flat bearing plate

9 adapted to slidably engage the bottom of the tray when the follower is being shifted and adapted to bear against the end of the stack of cards when the follower is in its operative position. Formed at the ends of the plate 9, are quadrants 10, which slidably engage the guides 7. The quadrants 10 are provided with arcuate bearing edges 11 which are shaped so that, when the follower is tilted to the position shown in Figs. 2, 60 3 and 4, the quadrants 10 bind between the bottom 4 and guides 7 for securing the follower against tilting.

Formed in the plate 9 adjacent the ends thereof, are recesses 12, which are adapted to receive the flanges 7 when the follower is tilted to its operative position.

Extending along one edge of the bearing plate 9, is a flange 13 arranged to provide a handle, whereby the follower may be shifted 70 75 along the tray and also tilted to its operative position.

In operation, to shift the follower along the tray, it is arranged so that the bearing plate 9 slidably engages the bottom of the 80 tray. When the follower has been shifted to the desired position, it is tilted substantially ninety degrees to position the bearing plate 9 in engagement with the end of the stack of cards. In this latter position, the 85 quadrants 10 are frictionally secured between the bottom 4 and guides 7.

When the stencils are being transferred to the tray from the addressing machine, not shown, the tray is placed at the outlet end 90 of the machine in a horizontal position so as to constitute a continuation of the guideway along which the stencils are fed. The follower is then in position to permit it to slide along the tray and, as the stencils are 95 ejected from the machine and enter the tray, the follower slides along the tray with the stencils for holding the latter edgewise in the tray.

Although but one specific embodiment of 100 this invention has been herein shown and described, it will be understood that numerous details of the construction shown may be altered or omitted without departing from the spirit of this invention as defined 105 by the following claims:

I claim:

1. A device of the class described, comprising a tray, a follower slidably supported in said tray, said follower being also tiltable, 110

and interengaging means on said tray and follower for frictionally securing said follower against shifting when the latter is tilted to one position.

5. 2. A device of the class described comprising a tray having a guideway, a follower slidably engaging said guideway, said follower being tilttable, and coacting shoulders on said tray and follower for frictionally securing said follower in its tilted position.

3. A device of the class described comprising a tray having a guideway, a follower slidably engaging said guideway, said follower being tilttable substantially ninety degrees, and coacting shoulders on said tray and follower for frictionally securing said follower in its tilted position.

4. A device of the class described comprising a tray having a guideway, and a follower 20 slidably engaging said guideway for movement longitudinally of said tray, said follower being tilttable through an arc of substantially ninety degrees to position a portion 25 thereof in frictional engagement with said guideway.

5. A device of the class described comprising a tray for cards, a follower having a bearing surface adapted to slidably engage the bottom of said tray, said tray being tiltable to bring said bearing surface into engagement with the stack of cards, and coacting means on said tray and follower adapted to frictionally secure said follower against shifting when tilted.

35. 6. A device of the class described comprising a tray for cards, a follower having a bearing surface adapted to slidably engage the bottom of said tray, said tray being tiltable to bring said bearing surface into engagement with the stack of cards, and interengaging shoulders on said tray and follower adapted to frictionally secure said follower against shifting when said bearing surface is positioned at substantially right angles to 40 the bottom of the tray.

7. A device of the class described comprising a tray having a guideway, and a follower having a quadrant slidable in said guideway, said follower being tilttable to position a portion of said quadrant in frictional engagement with said guideway for securing said follower against shifting.

55. 8. A device of the class described comprising a tray having a guideway, and a follower having a quadrant slidable in said guideway, said follower being tilttable through an arc of substantially ninety degrees to position a portion of said quadrant in frictional engagement with said guideway for securing said follower against shifting.

60. 9. The combination with a tray having a guideway, of a follower comprising a bearing plate slidable on the bottom of said tray, 65 a pair of quadrants arranged at the ends of

said plate for slidably engaging said guideway, and a handle on said bearing plate for shifting said follower along said tray and for tilting it to bring said plate into a position transverse to the bottom of the tray, 70 said quadrants being adapted to frictionally engage said guideway when the follower is tilted.

10. A device of the class described comprising a tray having a bottom and side 75 walls providing a guideway, inturned flanges on the upper edges of said side walls, a follower having a bearing plate slidably engaging the bottom of said tray, and quadrants arranged at the ends of said plate and slidably engaging said inturned flanges, said follower being tilttable to position said quadrants in frictional engagement with said flanges.

11. A device of the class described comprising a tray having a bottom and side walls providing a guideway, inturned flanges on the upper edges of said side walls, a follower having a bearing plate slidably engaging the bottom of said tray, and quadrants arranged at the ends of said plate and slidably engaging said inturned flanges, said follower being tilttable through an arc of substantially ninety degrees to position said quadrants in frictional engagement with said flanges.

12. A device of the class described comprising a tray having a bottom and side walls providing a guideway, inturned flanges on the upper edges of said side walls, a 100 follower having a bearing plate slidably engaging the bottom of said tray, and quadrants arranged at the ends of said plate and slidably engaging said inturned flanges, said flanges having recesses therein to permit the removal of said follower from said tray, 105 said follower being tilttable to position said quadrants in frictional engagement with said flanges.

13. A device of the class described comprising a tray having a bottom and side walls providing a guideway, inturned flanges on the upper edges of said side walls, a follower having a bearing plate slidably engaging the bottom of said tray, quadrants arranged at the ends of said plate and slidably engaging said inturned flanges, and a handle part extending along one edge of said plate for shifting said follower along said tray and for tilting it substantially 110 ninety degrees to position said plate at substantially right angles to said bottom.

14. A device of the class described comprising a tray having a bottom and side walls providing a guideway, inturned flanges on the upper edges of said side walls, a follower having a bearing plate slidably engaging the bottom of said tray, quadrants arranged at the ends of said plate and slidably engaging said inturned flanges, and a handle 115 125 130

part extending along one edge of said plate for shifting said follower along said tray and for tilting it substantially ninety degrees to position said plate at substantially right angles to said bottom, said quadrants being adapted to frictionally engage said guideway when said follower is tilted.

15. A device of the class described comprising a tray having a bottom and side walls providing a guideway, inturned flanges on the upper edges of said side walls, a follower

slidably and tiltably supported in said guideway, said follower having a bearing plate, and a pair of quadrants arranged at the ends of said plate and located between said side walls and inturned flanges, the radius of each of said quadrants being greater than the distance between the bottom of said tray and said flanges.

Signed at Chicago this 7th day of June, 1927.

PAUL A. GOLLNICK.
